RECORD CONTROLLED STATISTICAL
MACHINE

Arthur Thomas, Wallington, and Arthur William Excell, Thornton Heath, England, assignors to Powers Accounting Machines Limited, London, England, a British company

Application March 28, 1945, Serial No. 585,316
In Great Britain March 30, 1944

11 Claims. (Cl. 164—114)

1

This invention relates to record card controlled tabulating machines and has for its object to provide an improved mechanism for selecting and setting punches to represent the total held in an accumulator of such a machine whereby said total may be punched in a summary card.

To this end the invention comprises mechanism for selecting out of a column of record punches, a punch corresponding to the position of a swinging sector settable under the control of an accumulator wheel, said mechanism comprising in combination a column of slidably mounted punch setting elements, a selecting slide mounted to move along said column to position a lug thereon in register with each setting element in turn, an operating lever pivoted at one end to a fixed frame member and connected at its other end by a pin and slot connection to the selecting slide, and a link connecting the operating lever to an extension of the sector beyond its pivot, the distance from the pivot of the operating lever to the point of connection of the link thereto being substantially equal to the distance from the sector pivot to the point of connection of the link to the extension thereof, whereby as the sector swings through a series of consecutive numerical positions, the selecting slide moves in a straight line to bring its lug into register with the corresponding setting elements in turn, the selecting slides for a plurality of columns of punch setting elements being mounted in a frame capable of movement towards the punch setting elements to actuate said elements by engagement therewith of the lugs on the selecting slides.

The punches may be arranged in columns in the manner described in British patent specification No. 461,612, Francis G. English, accepted February 19, 1937, each column being provided with a corresponding column of set bars which are actuated through flexible cables by the punch setting elements above referred to.

In order that the invention may be more completely understood one embodiment thereof will now be described with reference to the accompanying diagrammatic drawings as applied to a machine having an accumulator and total taking mechanism of the form described in United States Patent No. 2,364,934 or 2,242,095, or in the copending U. S. application filed March 28, 1945, Serial No. 585,250 (Div. 17) of Arthur Thomas and Alfred Herrman Gausden for improvements in record card controlled statistical machines.

In the accompanying drawings:

Figs. 1A and 1B together form a left hand outside elevation of the machine;

2

Fig. 2 is a view of the upper part of the machine showing the accumulator wheels and the swinging sectors, together with the punch selecting mechanism in outside elevation;

5 Fig. 2A is a detail view of the sectors and connected parts;

Fig. 3 illustrates the punch selecting mechanism according to the invention in side sectional elevation, showing also certain mechanism for 10 selecting a punch to punch an indicating hole when the accumulator is clear;

Fig. 4 is a plan view of the mechanism shown in Fig. 3 omitting the mechanism for selecting the indicating hole punch; and

15 Fig. 5 is a plan of the mechanism for selecting the indicating hole punch.

In the drawings like references indicate the same or similar parts.

In the construction illustrated in the drawings, 20 stops 180 in a stop basket 161 are set by sensing mechanism which reads the cards, and swinging toothed sectors 160 are set from the stops, thereby setting also corresponding swinging type carriers 158 in the known manner.

25 Each type carrier 158 is connected by a link 157 to a corresponding toothed sector 155 from which the amounts read from the cards are transmitted to the positive accumulator wheels 150 or to the negative accumulator wheels 151 in the manner 30 described in U. S. Patent No. 2,364,934.

When the total accumulated in the wheels 150 or 151 is to be recorded the wheels are engaged with the sectors 155 before the latter are permitted to swing forward whereby the sectors are 35 set to the amount of the total and, through the links 157, set the type carriers 158.

In order to select punches in accordance with the value of the total the following mechanism according to the invention is provided.

40 This punch selecting mechanism comprises a pair of frame plates 351 each carrying blocks 352 whereby it is attached by screws 352A or any other suitable means to a bar 353 and blocks 353a on a side plate 354 of the upper part of the machine.

45 Mounted outside each plate 351 is a movable plate 355, the two plates 355 being connected by cross bars 356, 357 and a cross rod 358. The bar 357 and rod 358 are guided for movement in horizontal slots 359 and 360 respectively so that the frame constituted by the plates 355, bars 356, 357 and rod 358 is movable horizontally.

50 Mounted between the two bars 356, 357 is a series of vertical bars 361 upon each of which is 55 mounted a selecting slide 362, there being one

such vertical bar 361 and associated slide 362 for each column of punches, in the present instance eleven.

Each selecting slide 362 carries a projecting finger 363 and cooperating with each of said fingers is a column of punch setting plungers 364, there being ten such plungers 364 in each column representing the digital values 0 to 9.

In each column the plungers 364 are arranged horizontally one above the other with the lowest value plunger, i. e. zero, at the top and the cardinal numbers 1 to 9, inclusive, reading down from the zero.

Each of the selecting slides 362 is connected to the corresponding type carrier 158 of the adding mechanism by the following mechanism.

Freely mounted on a fixed shaft 365 is an operating lever 366 for each slide 362, the lever 366 carrying a pin 367 engaging a slot 368 in an extension 369 of the slide. The pivot 365 for the operating lever 366 is disposed below the level of the pin and slot connection 367, 368 by an amount approximately equal to half the vertical travel of the slide 362 so that the two extreme positions of the operating lever 366 are substantially equal distances above and below a horizontal line through the pivot 365. The lever 366 is however not straight but is curved so that it is concave downwardly.

The pivot 365 for the operating levers 366 is vertically above the shaft 159 upon which the sectors 158 are mounted and each type carrier 158 has an extension 370 beyond its pivot, which extension is substantially parallel to the part of the operating lever 366 adjacent to the pivot 365. This extension 370 of the sector is connected to the corresponding operating lever 366 by a vertical link 371, the distance of the pivot 365 from the point of connection 372 between said link 371 and the lever 366 being substantially the same as the distance from the sector pivot 159 to the point of connection 373 of the link 371 to the extension 370 of the sector.

By means of the connection above described, as the sector 158 swings through a series of consecutive numerical positions the selecting slide 362 moves in a straight line to bring its finger 363 into register with the corresponding setting plungers 364 in turn.

In this way when the sectors 158 are set from the accumulator wheels at a total taking operation each selecting slide 362 will be positioned with its finger 363 in register with a plunger 364 of the corresponding column representing the digit to which the sector has been set, the plungers thus selected representing the amount of the total.

Each plunger 364 is in register with an intermediate transmission pin 397 which is in register with a corresponding flexible cable 388 by means of which the corresponding punch is set for operation.

The punch unit, indicated generally in Fig. 1B, is the same as that described in British patent specification No. 490,358 and includes columns of punches 375 and corresponding columns of set bars 386, of which the upper ends are in register with the lower ends of the cables 388.

In order to operate the set bars 386 the horizontally movable frame 355 is actuated by a pair of vertical arms 400 secured at their lower ends to a shaft 401 and pivoted at their upper ends by a pin and slot connection 402 to the frame plate 355. The shaft 401 carries a horizontal lever 403 of which the free end has a pin 404 engaging in a slot in a vertical link 406, said link

terminating at its lower end in an eccentric strap 407 engaging over an eccentric 408 secured to a shaft 409 carrying a pinion 410 meshing with a gear wheel secured to a shaft 412 driven from the mainshaft 2 by a Geneva mechanism indicated generally at 413, in such a way that the eccentric 408 makes one revolution in each revolution of the mainshaft 2, the revolution of the eccentric occupying a quarter of the revolution of the main shaft. The pin 404 on lever 403 is normally at the bottom of the slot 405 in the link 406 in which position it is held by springs 414 attached to the vertical arms 400, these springs maintaining the plates 355 against stops 418 constituted by the extended ends of the shaft 365, the frame being thus in a retracted position away from the plungers 364. The vertical link 406 is stationary at the top of its stroke during three quarters of the revolution of the main shaft 2 and during this period the moving frame 355 is locked in the retracted position by engagement of the pin 404 with the bottom of the slot 405, and by engagement of the plates 355 with the stops 418.

During a quarter of each revolution of the main shaft 2 the eccentric 408 makes its revolution and moves the link 406 down and up but this movement is without effect on the frame 355, which is held in the retracted position by the springs 414, the slot 405 sliding idly past the pin 404.

Also pivoted to the lever 403 is a depending link 415 of which the lower end is forked at 416 to engage over a pin 247 on a link 243. The link 415 carries a lug 417 which is normally clear of a lug 418 on the link 406.

During card reading cycles the link 243 is stationary and the vertical reciprocations of the link 406 move the lug 418 idly past the lug 417 without affecting the link 415. At a total taking operation, however, the total shaft 235 makes one revolution and a cam 236, thereon, through link 238, bell crank plate 239, and link 240 rocks arm 241 whereby the link 243 is moved to the right in Fig. 1A. Consequently the pin 247 swings the link 415 counterclockwise into a position in which its lug 417 is beneath the lug 418 so that now, when the link 406 next moves down, its lug 418 engages lug 417 and pulls link 415 downwardly, thereby rocking the lever 403 and shaft 401 counterclockwise, thus rocking the vertical levers 400 to move the frame 355 to the left in Fig. 1A so that the setting plungers 364 are actuated by the fingers 363 on the selecting slides 362. This actuation of the plungers operates the punch set bars 386 through the flexible cables 388 whereby the set bars are set to the amount of the total.

On the rise of the link 406 the springs 414 return the frame 355 to its normal position.

The machine also includes means for sensing the sectors 158 on a total taking operation and means operative under the control of said sensing means to give an indication when any sector is away from the zero position, thereby indicating whether the accumulator associated with said sector is clear.

This mechanism includes a shaft 420 mounted between wings 421 upstanding from a plate 422 supported on a bar 423 extending across the frame plates 355 and supported thereon. Thus the shaft 420 moves bodily with the frame 355.

Pivoted on shaft 420 is a series of levers 424 each urged by a spring 425 into engagement with a sensing pin 426 resting on a corresponding one

of the fingers 363 which project from the selecting slides 362.

If any sector 158 moves away from zero the corresponding selecting slide 362 moves down and the sensing pin 426 follows it, thereby permitting the corresponding lever 424 to rock clockwise.

Lying across the tails 424a of all the levers 424 is a ball 427 carried between arms 428 pivoted on shaft 420 and one of said arms 428 has an extension 429 designated as "clear" which when all the sectors are at zero is in register with a plunger 364a also designated as "clear" connected by one of the flexible cables 388 to a set bar 386 for setting a punch to punch "clear" indicating hole on the card.

If any sector moves away from zero, the corresponding sensing pin 426 is free to move down and consequently the corresponding lever 424 rocks counterclockwise and its tail 424a lifts the ball 427 thereby depressing the extended arm 429 out of register with the plunger 364a, so that if the total is not zero the indicating hole is not punched. To prevent upward overthrow of extension 429 when levers 424 are restored to zero position, use is made of a rocker lever 420a whose extension 420b is urged by spring 420c against the underside of the tails 424a.

The punching mechanism is similar to that described in British patent specification No. 490,358, Ernest C. McClure, accepted August 12, 1938, being driven from a punch shaft which is rotated at the proper time through a clutch controlled by a cam on the total shaft 235.

We claim:

1. Mechanism for selecting out of a column of record punches, a punch corresponding to the position of a swinging sector settable under the control of an accumulator wheel, said mechanism comprising in combination, a column of slidably mounted punch setting elements, a selecting slide, a lug on said slide, said slide being movable along said column to position its lug in register with each setting element in turn, a support, an operating lever pivoted at one end to said support, a pin and slot connection between the other end of said operating lever and said selecting slide, an extension to said swinging sector, said extension projecting beyond the pivot about which said sector swings, and a link connecting said operating lever to said sector extension, the distance from the pivot of the operating lever to the point of connection of said link thereto being substantially equal to the distance from the sector pivot to the point of connection of said link to said sector extension.

2. Punch selecting mechanism according to claim 1, wherein the selecting slides are mounted in a frame movable towards the columns of punch setting elements to actuate those of said setting elements in register with which the lugs of the selecting slides have been positioned.

3. Punch selecting mechanism according to claim 1 wherein the selecting slides are vertical and the operating levers therefor are horizontal, and the pivot for each operating lever is disposed below the level of the point of connection of the operating lever to the slide by an amount approximately equal to half the vertical travel of the slide, so that, the two extreme positions of the operating lever are substantially equal distances above and below a horizontal line through the operating lever pivot.

4. Punch selecting mechanism according to claim 1 wherein the extension of the sector is substantially parallel to the part of the operating

lever adjacent the pivot therefor, and the link connecting said extension and lever lies parallel to the direction of the column of punch selecting elements.

5. In a machine of the character described, the combination with a type carrier and an accumulator wheel for controlling the movement of the carrier, of punch setting means corresponding to zero and clear designations respectively, means for operating said punch setting means, one of said operating means being adjustable into and out of alignment with the punch setting means designated zero, and the other of said operating means being movable into and out of alignment with the punch setting means designated clear, means for actuating said adjustable operating means, and means associated with said adjustable and movable operating means for adapting the latter to move out of alignment with the punch setting means designated clear when the adjustable operating means moves out of alignment with the punch setting means designated zero.

6. In an accounting machine having an accumulator and swinging sectors settable from said accumulator to record the total held therein, an indicating element to each sector, disposable in a "non-clear" position indicating that the accumulator is not clear, or in a "clear" position in which it indicates that the accumulator is clear, a frame movable towards said indicating element, a plurality of slides mounted in said frame, one slide to each sector, an operative connection between each sector and its corresponding slide, a sensing pin to each slide, a shaft mounted in said frame, a plurality of levers pivoted on said shaft, each of said levers spring urged into engagement with a corresponding one of said sensing pins, a ball pivoted on said shaft and disposed across all said levers, and an extended arm to said ball in the plane of the indicating element.

7. In an accounting machine having accumulators, and type carriers adjustable by said accumulators to record a total held in the latter, the combination with a punch unit, of numerical punch setting means and clear punch setting means, means for operating all of said punch setting means including a member movable upon total taking action of said machine and extension means on said member, means adjustable by the carriers for aligning some of the extension means with numerical punch setting means corresponding to the adjusted positions of said carriers, and means controlled by the aligning movement of said aligned extension means for adapting another extension means for movement out of alignment with said clear punch setting means.

8. In an accounting machine, in combination, means for setting numeral and clear punches, extensions for aligned operating engagement with said punch setting means, means for variably adjusting the extensions adapted for operating engagement with the numeral punches including a movable accumulator controlled type carrier, means for moving the extensions to actuate the punch setting means, means for sensing adjusting movement of said numeral punch setting extensions and means controlled by said sensing means for affecting non-alignment of the clear punch operating extension and said clear punch setting means when adjusting movement of a numeral punch setting extension is sensed.

9. In an accounting machine, in combination, punch setting means, extensions for operating said setting means, means for moving the exten-

sions including a movable frame and an operating lever therefor, an operating link and a total link extending from said lever, said operating link having free movement relatively to said lever, means for reciprocating said operating link, coacting means on said links for operatively joining them and means for moving said total link into operative engagement with said operating link for transferring the motion of the operating link to said lever through said total link.

10. In an accounting machine, in combination an accumulator, a type carrier movable under control of said accumulator for recording numerical items and totals thereof, a movable frame, a group of punch setting plungers, a separate punch setting plunger, means movable mounted on said frame for actuating said group plungers, a lever connecting said actuating means and the carrier whereby said actuating means can be moved successively past the plungers of said group for register with a plunger corresponding to the recording movement of said carrier, mechanism on said frame, sensing means associated with said mechanism and said actuating means whereby movement of the latter to and from an extreme position will adapt said mechanism for movement, and operating means for said sepa-

rate punch movable into and out of alignment with the punch by said mechanism.

11. In an accounting machine, in combination, an accumulator controlled type carrier, means for setting punches corresponding to numeral and clear designations respectively, means for operating the punch setting means including a movable frame and arm for moving the frame and punch setting extensions associated with said frame, means operated by the carrier for adjusting the punch setting extensions corresponding to numerical designations, sensing means controlled by the adjusting movement of any of said numeral punch setting extensions away from a position designated as zero for disabling the punch setting extension designated as clear, an operating link and a total link associated with said frame moving arm, means for reciprocating said operating link in free movement relatively to said arm, coacting means on said links for operatively joining them, and means for moving the total link into coactive relation with said operating link for transferring motion from the latter to said frame operating arm through said total link.

ARTHUR THOMAS.
ARTHUR WILLIAM EXCELL.
